W. S. SETTLE

GARMENT HANGER

Filed Dec. 27, 1923

UNITED STATES PATENT OFFICE.

WITCHER S. SETTLE, OF NEW YORK, N. Y.

GARMENT HANGER.

Application filed December 27, 1923. Serial No. 682,954.

To all whom it may concern:

Be it known that I, WITCHER S. SETTLE, a citizen of the United States, residing at New York, in the county of New York and 5 State of New York, have invented certain new and useful Improvements in Garment Hangers, of which the following is a specification.

This invention relates to garment hangers 10 of the usual shoulder formation, the hanger having means along its upper edge, visible from both sides, for indicating the size of the garment hung thereon, such indicator being movable to permit of adjustment at 15 will thereby enabling its use to successively display garments of various sizes. The invention further contemplates the formation of raised shoulders at either side of the central portion of the hanger around which 20 central portion the neck of the garment fits, thus preventing accidental slipping of the garment off of the hanger, and positioning the garment so the indicator may be seen without obstruction.

25 It is the usual practice of clothing manufacturers, wholesale stock houses, and department stores to identify the garment as to size by affixing a tag to it. To ascertain the size of any one of a collection of such 30 garments necessitates a time-consuming and cumbersome search for its particular tag. By the use of the present garment hanger the indicator shows at a glance the size of the garment sought. This results in a great 35 saving of time and labor.

Among the objects of the present invention are the provision of a garment hanger of the character described which will securely hold the garment against accidental 40 slipping and displacement, while permitting of ready placing and removal thereof; and the combination with such a hanger of adjustable and visible means for enabling a quick and easy determination of the size, 45 of the garment hung thereon.

In the accompanying drawing there are shown two specific embodiments of the present invention;

Figure 1 is a plan view of a preferred 50 form of the invention;

Figure 2 is a top view of the garment hanger shown in Figure 1, the central hook being omitted for clearness;

Figure 3 is a detail cross-section view 55 taken on line 3—3 of Figure 1;

Figure 4 is a plan view of a modification of the present invention;

Figure 5 is a top view of the modification shown in Figure 4, the central hook being omitted for the sake of clearness; and 60

Figure 6 is a detail cross-section taken along line 6—6 of Figure 4.

Referring to the drawings:

In Figure 1 the numeral 1 indicates the body portion of a garment hanger constructed in accordance with the present invention. The hanger is of the usual shoulder formation, that is, curved downwardly at its ends. Along the upper edge of the hanger 1 shoulders 2 are provided equidistant from hook 3 which is mounted centrally in the customary manner. The provision of such shoulders produces a central portion of considerably greater width than the ends, the wide central portion being grooved 75 throughout its length and along its upper edge as shown at 4. U-shaped guide members 5 and 6 are permanently fixed to the upper edge of the central portion of the hanger at either side of hook 3. Indicators, 80 preferably of spherical shape, such as are shown at 7 and 8 are mounted for sliding movement upon the U-shaped members 5 and 6 respectively. These indicators may be small wooden balls of various colors, such as red and green, used to indicate different 85 groups of sizes. Thus, for instance, red may indicate the small sizes and green the large sizes. It is not to be understood that any limitation or restriction of the colors used 90 is contemplated, the use of colors being entirely a matter of preference.

The bottom of groove 4 is formed with a plurality of spaced indentations 9 acting as pockets in which members 7 and 8 rest 95 thereby preventing their accidental displacement when the garment hanger is in use. This same function may be performed with the elimination of indentations 9 by forming the wire guide members 5 and 6 with a 100 series of downwardly extending loops or waves. Thus, when the indicator pieces are slid along the guide wire they will be frictionally held against the upper edge of the hanger or indicator plate at intervals due 105 to the wave-shape of such guide wire. An important feature of this embodiment is the ready attachment of the combined scale and shoulder formation to the ordinary coat hanger.

A length of wire 10 is bent to the general shape of a double-U, the adjacent arms 11 and 12 being bent as at 13 to encircle the stem of hook 3. The outside arms of the 5 U-formation are bent at 14 and 15 to engage the lower curved edge of hanger 1. The natural resiliency of wire 10 is such that it is held firmly in engagement with the hanger yet can be easily removed by the 10 application of pressure to release the bent or hook portions 14 and 15 from the lower curved edge thereof. Wire 10 serves as a framework for a sheet metal indicating face-plate 16 bearing a suitable scale. This 15 face-plate is fixed to the wire framework in the manner shown in detail in Figure 6. Flanges are formed along the upper and side edges of plate 16, these flanges being bent around the wire 10 to rigidly and permanently attach the face-plate thereto. The 20 upper edge of the face-plate is notched at intervals, as indicated at 19, to assist in the accurate placing of the indicator piece 20 and to prevent its accidental displacement. Indicator piece is also made of sheet metal 25 bent around the face-plate and freely slideable thereon. Its upper edge is slotted to form a tongue 21 which is crimped to insure its positive engagement with notches 19. 30 The arms of wire 10 of which hook portions 14 and 15 are extremities, cooperate with the garment hanger to form shoulders which prevent the accidental slipping of any garment hung thereon in the manner 35 previously described.

What I claim is:—

1. In an indicating garment hanger, the combination with a shoulder form, of an indicator frame attached to said shoulder form and an adjustable indicator on said frame.
2. In an indicating garment hanger, the combination with a shoulder form, an indicator frame attached thereto, and an ad-

justable indicator on said frame, of means 45 forming an operative connection between the frame and a part of the shoulder form for stationing the indicator in various positions.

3. In an indicating garment hanger, the 50 combination with a shoulder form, and an indicator frame attached thereto, and having an adjustable indicator thereon, of means cooperating with the indicator for positioning it at any one of a plurality of 55 points along said frame.

4. A garment hanger comprising a shoulder form having its upper edge grooved, indentations formed at intervals along said groove, a guide spaced from the 60 upper edge of the shoulder form and parallel therewith, and balls slideable along said guide and in said groove.

5. In combination, a garment hanger comprising a curved lower edge an upper 65 edge curved throughout a portion of its length, the remaining portion of its length being raised and of straight line form, together with indicating means formed along the straight line edge. 70

6. A garment hanger comprising a shoulder form having a central portion, depending arms from either side thereof for reception of the garment, in combination with an indicator attached to the said central portion and means for positioning the indicator in any one of a plurality of points 75 with respect to said central portion.

7. A garment hanger comprising a shoulder form, indicator supporting means 80 attached thereto, and a movable visible indicator supported by said means and arranged for positioning at different points along said form.

In testimony whereof, I have hereunto 85 affixed my signature.

WITCHER S. SETTLE.
